UNITED STATES PATENT OFFICE.

ARTHUR MEDE, OF CARLSTADT, NEW JERSEY, ASSIGNOR TO NORMA-HOFFMANN BEARINGS CORPORATION, OF NEW YORK, N. Y., A CORPORATION OF NEW YORK.

TEXTILE SPINDLE.

Application filed June 20, 1919, Serial No. 305,651. Renewed August 18, 1923.

This invention relates to textile spindles and has for its primary object to provide an improved spinning spindle which is provided with a self-contained lubricant receiving reservoir which may be bodily removed with the spindle and its support from the bolster.

It is another and more particular object of the invention to provide means particularly designed for use in connection with silk spinning spindles, and including a bolster mounted in the supporting rail for yieldable oscillating movement, said bolster having a tapering socket or bore, a spindle support consisting of a tubular body section and a section fitted within one end of said tubular section and having a shank for frictional engagement in the bolster socket, said latter section of the support being formed 20 with a lubricant receiving cavity or pocket into which the lower end of the spindle extends.

It is a further general object of my invention to provide a spinning spindle as above characterized which consists of relatively few parts all very simply formed and which are capable of being easily and quickly assembled or disassembled.

With the above and other objects in view, the invention consists in the improved construction, combination and arrangement of the several elements as will be hereinafter more fully described, illustrated in the accompanying drawing and subsequently incorporated in the subjoined claims.

In the drawing wherein I have illustrated one practical embodiment of my invention and in which similar reference characters designate corresponding parts throughout the several views:

Fig. 1 is a vertical sectional view of a textile spindle constructed in accordance with one embodiment of the invention; and

Fig. 2 is a section taken on the line 2—2 of Fig. 1.

Referring in detail to the drawing, 5 designates the rail of a spinning machine having an opening therein to receive the shank of a bolster 6. This bolster at its upper end is formed with a head or flange 7 engaging the upper surface of the rail. A washer of felt, leather or other suitable material indicated at 8 surrounds the shank of the bolster and is held against the under side of the rail by a coil spring 9. The

lower end of the bolster shank is threaded to receive a nut 10 whereby the tension of the spring 9 may be regulated as desired.

The head 7 of the bolster is formed upon its perimeter with an upwardly and laterally projecting arm 11 in the upper end of which a sliding pin 12 is mounted. The bolster 6 is further formed with an axially extending tapered socket or bore 13.

The spindle support as herein shown consists of a tubular body section 14 open at its opposite ends. The ends of this tubular support 14 are counterbored to provide the annular shoulders 15 and 16 respectively. The outer race rings 17 and 18 of the upper and lower ball bearings engage against the shoulders 15 and 16 and have a tight mechanical fit within the counterbored ends of the support 14. In the lower end of this support the base section 19 has a driven fit. 70 This base section is formed with a shank 20 which is adapted to be tightly fitted and frictionally held within the socket 13 of the bolster. This shank is preferably tapered and so formed as to be freely removable 80 from the socket 13. The upper end of the base section 19 of the support also engages the outer race ring 18 and thus securely holds this ring upon the shoulder 16 and against longitudinal shifting movement. 85 The base section 19 is formed with a cavity or chamber 20 to receive a suitable lubricant, in which the lower end of the spindle is submerged.

The spindle 21 is formed with a diametrically reduced portion 22 to thereby provide the shoulder 23 against which the inner race ring 24 of the upper ball bearing is engaged, said race ring having a tight fit around the reduced portion of the spindle. 90

25 designates the ball bearings interposed between the race rings 17 and 24 and engaged in suitable races formed thereon. The lower end portion of the spindle is again reduced in diameter as seen at 26, said 100 end portion of the spindle extending into the lubricant contained in the cavity 20. A second shoulder 27 is thereby formed upon the spindle with which the inner race ring 28 of the lower ball bearing is engaged. 29 designates the bearing balls which are interposed between this ring and the outer race ring 18. These upper and lower ball bearings which support the 105 spindle for free rotation within the tubular 110

supporting member 14 may be of any approved type.

The spindle is also formed with a longitudinal bore or duct 30 extending through the reduced portions 22 and 26 thereof and opening through the latter portion of the spindle and in communication with the lubricant containing cavity 20. The upper end of this bore is transversely extended 10 through the spindle as at 31 and opens upon the periphery thereof immediately adjacent the upper ball bearing.

32 designates the whirl with which the driving band or belt is adapted to be engaged. This whirl, which is in the form of a sleeve, surrounds the tubular supporting member 14. At its upper end the wall of the whirl is relatively thick and formed with an internal annular flange 33 which 20 projects downwardly into the upper end of the supporting member 14. This end of the whirl is securely fixed upon the body of the spindle 21. At its lower end the whirl sleeve is provided with an outwardly projecting annular flange 34, and the inner end of the pin 12 mounted in the arm 11 overlies this flange and acts as a stop to prevent vertical lifting movement of the spindle and its support with respect to the bolster.

The wall of the supporting member 14 immediately above the lower bearing is provided with an opening 35 through which the lubricant may be fed into the chamber 20. The whirl sleeve is also provided with a plurality of openings 36 adapted to coincide with the opening 35 and affording a means to supply oil to the chamber or cavity 20.

40 From the foregoing description considered in connection with the accompanying drawing, the construction of my improved spindle will be fully understood. In the rotation of the sleeve whirl and spindle at 45 high speeds, the centrifugal force induces a suction through the bore or duct 30 in the spindle whereby the lubricant oil is drawn upwardly from the chamber 20 and thrown outwardly through the upper end of the 50 said duct upon the parts of the upper ball bearing. The oil will fall through the passage between the wall of the sleeve 14 and the periphery of the spindle and thereby also thoroughly lubricate the parts of the 55 lower ball bearing and finally return to the cavity 20. Thus, in the rotation of the spindle the level of the oil will be lowered so that it will not be thrown upwardly by 60 agitation above the lower ball bearing and not escape through the opening 35 in the sleeve 14. By the provision of this oil chamber or reservoir contained within the spindle and whirl support, it will be observed that the spindle together with said 65 support may be lifted as a unit and removed

from the bolster 6. Thus spindles of different sizes may be interchanged, or broken spindles quickly removed for any necessary attention. The several parts of the device are also of relatively simple form, and may 70 be produced in large quantities at a comparatively small manufacturing cost. It will be understood that the bolster mounting as illustrated in the accompanying drawings is merely conventional, and that various 75 other ways of mounting this bolster may be adopted.

While I have herein shown and described the preferred form, construction and relative arrangement of the various elements, it 80 is manifest that the invention may also be exemplified in numerous alternative embodiments and I therefore reserve the privilege of adopting all such legitimate changes as may be fairly embodied in the spirit and scope of the invention as claimed.

I claim:

1. A textile spindle comprising a tubular member having internal reduced portions at its upper and lower ends forming shoulders, bearing rings within the tubular member and resting against the shoulders, a base section removably secured in the lower end of the tubular member and holding the lower bearing ring against the shoulder, and having an oil receptacle in its upper face, a supporting shank carried by the lower end of the base section, and a spindle shaft extending down through the tubular member and carrying bearing rings arranged opposite 90 the bearing rings of the tubular member, and having its lower end extending within the oil receptacle of the base section, and having a passage extending longitudinally therethrough for supplying oil to the upper 95 bearing.

2. A textile spindle comprising a tubular member having internal enlarged portions at its upper and lower ends, bearing rings within the enlarged portions of the tubular member and resting against the shoulders, a base section removably secured in the lower end of the tubular member and holding the lower bearing ring against the shoulder, said base section having an oil receptacle in its lower face, and a supporting shank at its lower end, a spindle shaft having two shoulder portions carrying bearing rings cooperating with bearing rings of the tubular member, and having its lower 110 end extending within the oil receptacle in the base section, and said spindle shaft having a vertical passage extending from its lower end to the upper bearing ring.

3. A textile spindle comprising a tubular 125 member, bearing rings within the upper and lower ends of the tubular member, a base section fitting within the lower end of the tubular member, and holding the lower bearing ring in position, and having an oil re-

- ceptacle in its upper face, and a shank at its lower end, a spindle shaft passing through the tubular member and having bearing rings cooperating with the bearing rings of the tubular member and having its lower end extending within the oil receptacle, and a housing carried by the spindle and enclosing the tubular member, and having an annular flange extending into the tubular member for holding the upper bearing ring in position.
4. A textile spindle comprising a tubular member having internal reduced portions at its upper and lower ends forming shoulders, bearing rings within said tubular member and resting against said shoulders, a base section removably secured in the lower end of the tubular member and holding the lower bearing ring against the shoulder, said base section having an oil receptacle in its upper face, and a shank at its lower end, a spindle shaft having stepped portions carrying bearing rings cooperating with the bearing rings carried by the tubular member, and having its lower end extending within the oil receptacle of the base section, said spindle shaft having a vertical passage ex-
- tending from its lower end to the upper bearing ring.
5. A textile spindle comprising a tubular member open at both ends and having internal shoulders at its upper and lower ends, bearing rings within the tubular member and resting against the shoulders, a base section removably secured in the lower ends of the tubular member, and holding the lower bearing ring against the shoulder, said base section having an oil receptacle in its upper face, and a shank at its lower end, a spindle shaft having stepped portions carrying bearing rings cooperating with the bearing rings of the tubular member, and having its lower end extending within the oil receptacle of the base section, and a housing carried by the spindle and enclosing the tubular member, and having an annular flange extending within the tubular member, and holding the upper bearing ring against its shoulder.
- In testimony that I claim the foregoing as my invention, I have signed my name here-inunder.

ARTHUR MEDER.
